DESIGN FOR AN OIL BURNER PUMPING
AND CONTROL UNIT

Thomas W. Murphy, Penn Valley, Pa., assignor
to Monarch Manufacturing Works, Inc., Phila-
delphia, Pa., a corporation of Delaware

Application November 29, 1938, Serial No. 81,452

Term of patent 14 years

To all whom it may concern:

Be it known that I, Thomas W. Murphy, a citizen of the United States, and a resident of Penn Valley, Lower Merion Township, in the county of Montgomery and State of Pennsylvania, have invented a new, original, and ornamental Design for an Oil Burner Pumping and Control Unit, of which the following is a specification, reference being had to the accompanying drawings, forming a part thereof.

Figure 1 is a top plan view of an oil burner pumping and control unit, showing my new design,

Figure 2 is a front elevation of same,

Figure 3 is a bottom plan view of the same,
Figure 4 is a rear elevation of the new de-
sign,

Figure 5 is a side elevation looking in the di-
rection of the arrow A in Figure 4, and

Figure 6 is a side elevation looking in the di-
rection of the arrow B in Figure 4.

In Figure 1 the pump shaft has been broken
off for convenience of illustration.

I claim:

The ornamental design for an oil burner pump-
ing and control unit, as shown.

THOMAS W. MURPHY,
